UNITED STATES PATENT OFFICE.

EDWARD J. OVINGTON, OF BROOKLYN, NEW YORK.

DESIGN FOR A LAMP.

SPECIFICATION forming part of Design No. 12,771, dated February 14, 1882.

Application filed January 17, 1882. Term of patent 3½ years.

To all whom it may concern:

Be it known that I, EDWARD J. OVINGTON, of Brooklyn, Kings county, New York, have invented a new and original Design for a Lamp, of which the following specification is a full, clear, and exact description, reference being had to the accompanying drawing, forming part of this specification.

The drawing represents a perspective view of my newly-designed lamp.

This invention relates to a new configuration for an oil or gas lamp.

It consists of a base-plate, *a*, having a rim, *b*, and uprights *c c* at opposite sides, the uprights being fastened at their upper ends to the body *d* of the lamp in such a manner that the lower portion of said body *d* projects between said uprights. *e* is a ring, which may

be fastened to the uprights *c*, so as to surround the body *d*, as shown.

My newly-designed lamp is of graceful appearance. It may be ornamented in suitable manner. Its base may be used as a card-receiver, if desired.

I claim as my invention—

1. The design for a lamp, consisting of the base *a*, having rim *b*, and of the uprights *c c* and body *d*, substantially as shown.
2. The design for a lamp, consisting of base *a*, with rim *b*, and of the uprights *c c*, body *d*, and ring *e*, substantially as shown.

EDWARD J. OVINGTON.
